UNITED STATES PATENT OFFICE.

WILLIAM FESSENDEN BEASLEY, OF OXFORD, NORTH CAROLINA.

SEAL-LOCK.

SPECIFICATION forming part of Letters Patent No. 439,623, dated November 4, 1890.

Application filed May 28, 1889. Serial No. 312,383. (Model.)

To all whom it may concern:

Be it known that I, WILLIAM FESSENDEN BEASLEY, a citizen of the United States, residing at Oxford, in the county of Granville and State of North Carolina, have invented 5 certain new and useful Improvements in Seal-Locks; and I do hereby declare the following to be a full, clear, and exact description of the invention, such as will enable others skilled in 10 the art to which it appertains to make and use the same.

My invention relates to certain new and useful improvements in seal-locks; and it consists in the combination of a sliding bolt having 15 a slot for the reception of the seal with a register, so that on each unlocking motion of the bolt the register is actuated, recording such motion, and in details of construction thereof, as will be hereinafter more fully described 20 and claimed.

Referring to the accompanying drawings, in which corresponding parts are designated by corresponding letters, Figure 1 is a side view of my invention with the cover removed. 25 Fig. 2 is a longitudinal central section thereof, the cover being on. Fig. 3 is a plan view of a lock differing slightly from that shown in Figs. 1 and 2, but also of my invention, the cover thereof being removed. Fig. 4 is a detail perspective view of the sliding bolt. Fig. 5 is a detail perspective view of the dogs. Fig. 6 is a detail side view of the slide E. Fig. 7 is a cross section on line x x of Fig. 1, with the bolt removed.

35 The base-plate A has in its ends holes a to receive bolts, nails, &c., for securing it in position, and has formed upon the central portion of its face longitudinal walls a' a², the said walls abutting at one end against the 40 transverse wall a³, which is separated from a second transverse wall a⁴ by a channel a⁵, the said channel being adapted to receive a hasp of any suitable form. The opposite ends of the walls a' a² are contiguous to the shoulders 45 a⁶ formed on either side of the plate A. The

second transverse wall a⁴ is provided with a recess a⁷ and serves as a keeper for the bolt.

The bolt B is provided on the forward end of its face with a handle b and a rib b', the 50 latter having a slot b² to receive the continuous ring c of the seal C. The lower surface of the bolt slides upon the face of the walls

a' a², and has in the middle of its rear end a post b³, which slides in the channel a⁵ between the said walls a' and a², one face of the said 55 projection having a notch b⁴ and beveled ends b⁵ and b⁶. A lug b⁷ is also formed on the rear end of the lower surface of the said bolt, but on one side thereof, to actuate the register, as will be hereinafter described. 60

In a recess a⁸ formed in the longitudinal wall a' are pivoted dogs D, the noses d of which project into the longitudinal channel a⁵, being normally held in that position by springs d'. A slide E rests beside the wall 65 a² and has shoulders e e' on its forward and rear end, respectively, being held in position by a screw e² let into the plate A. Projecting from the rear end of the slide and attached thereto is a trip-lever e³, the free end 70 of which is held against the cog-wheel f by means of a spring e⁴.

On the shaft F, carried by the shoulders a⁶ of the base-plate are a series of wheels f, f', f², and f³. Each of these wheels has impressed on a part of its periphery the successive numbers from 0 to 9, inclusive, while a series of recesses f⁴, forming cogs, are placed in the remaining portion thereof, each recess being opposite a number. On the shaft G, 80 also supported by the shoulders a⁶ of the base-plate, and which is parallel to the shaft F, are a series of gear-wheels g, g', and g², separated from each other by sleeves g³ upon the shaft G. Each of the wheels g, &c., has 85 a crown-gearing formed by pins g⁴, projecting from a face thereof, and a spur-gearing formed by a corresponding number of shoulders g⁵ on its periphery. The pins g⁴ gear with the recesses f⁴ on the wheels f', f², and 90 f³, while the shoulders g⁵ are struck by pins f⁵, projecting from the sides of the wheels f, f', and f², each of the said wheels having such a pin. A spring-catch f⁶ is attached to one of the shoulders a⁶, and by engaging in 95 the recess f⁴ of the first wheel f prevents its backward rotation.

A cover H fits over the base-plate from the transverse wall a³ to the opposite end thereof, covering the hereinbefore-described mechanism, and is provided with a slot h, having a glass h', through which the state of the register may be taken. The operation of my device is as follows: The bolt B is first pushed

under the cover H as far as possible, as indicated in dotted lines in Fig. 2, thus leaving the channel a^5 open. The hasp is now inserted therein and the bolt withdrawn to its full extent. In so doing the forward beveled end b^5 of the post b^3 will strike the dogs D and throw them back into the recess a^9 , thus permitting the post to slide along the channel a^8 to its forward end, after the passage of which the spring d' will throw the nose of the dogs back into the channel behind the said post. The lug b^7 will also strike the forward shoulder e of the slide E and draw the latter forward, the said parts now having the position shown in Figs. 1 and 6. The bolt is then shoved in or backward until it assumes the position shown in full lines in Fig. 2, and in so doing the rear beveled end b^6 of the post b^3 will strike the noses d of the dogs D, forcing them back to permit its partial passage; but the springs d' will again throw them out, so that they engage the notch b^4 in the post b^3 , as shown in Fig. 5. The dogs thus prevent a forward, but not a backward, movement of the bolt, the latter being prevented by the ring c of the seal contained between the slot b^2 of the bolt and the end of the cover H. If it is now desired to remove the hasp, it is necessary to shove backward the bolt, and this can only be done by breaking the ring c of the seal and removing it from the recess b^2 . As in some instances it may be possible for other seals to be obtained and inserted in lieu of the broken ones, thus leaving no traces of the lock having been tampered with, I provide the above-described recording device, which serves to record the unlocking, for as the bolt is shoved backward after the seal has been broken the lug b^7 thereon will strike the rear shoulder e' of the slide E and thus carry the latter back with it. The rear end of the trip-lever e^3 will then engage a recess f^4 in the wheel f and move the latter one space forward, causing a correspondingly-higher number to appear under the slot h of the cover, by which means it may be readily ascertained whether the device has been unlocked between any two successive readings of the register. In case the wheel f , &c., is already recording its highest number 9 the pin f^5 will strike a shoulder g^5 of the wheel g , &c., thus moving the latter the distance of a pin g^4 thereon, which motion will be again transferred to the succeeding wheel f' , &c., moving the latter the distance of a recess f^4 and causing a correspondingly-higher number on such wheel to appear under the slot h of the cover. It will thus be seen that one revolution of one of the wheels f , f' , or f^2 means one-tenth of a revolution of the succeeding wheel f' , f^2 , or f^3 , and that the numbers on the first wheel f designate units, on the second f' tens, on the third f^2 hundreds, and on the fourth f^3 thousands, and that by the

above-described arrangement of wheels I can record nine thousand nine hundred and ninety-nine unlockings. 65

In Fig. 3 I have represented as an additional safeguard a key-lock, in which case I represents a post to receive the barrel of a key, which when partially turned will strike the dog i , forcing it into the notch i' in the bolt B, locking the latter in position, while if the key is still further turned it will strike the arm i^2 of the pawl i^3 , and thus, by means of the arms i^4 and i^5 on the pawl and dog respectively, withdraw the latter from the bolt and unlock it. In this figure, and in Fig. 4 also, a spring trip-lever J is applied directly to the lug b^7 on the bolt instead of being attached to the slide E, and serves the same purpose as the trip-lever e^3 . 75

Having thus described my invention, what I claim, and desire to secure by Letters Patent, is— 85

1. The combination, with a sliding bolt having an open slot therein adapted to receive a seal, of means for preventing the forward movement thereof, a trip-lever actuated by the bolt, and a registering mechanism driven by the said trip-lever, as described. 90

2. The combination, with a suitable casing, of a sliding bolt having an open slot therein and a projection thereon in the interior of the casing, pivoted dogs engaging the said projection, springs attached to the said dogs throwing their noses behind their pivotal points, a slide carrying a trip-lever actuated by the bolt, and wheels having numbers therein actuated by the trip-lever, as described. 95

3. The combination, with a sliding bolt having a slot therein and a projection thereon, of spring-dogs engaging the said projection, an independent slide having projections upon its forward and rear ends and carrying a trip-lever, and a registering device driven by the said trip-lever, as described. 100

4. The combination, with a sliding bolt having an open slot therein and a projection thereon, a spring-actuated dog engaging the said projection on the sliding bolt, a trip-lever actuated by the backward movement of the said bolt, and a registering device actuated by the said trip-lever, as described. 110

5. The combination, with a locking-bolt having a slot therein, of a seal contained in the said slot, a post upon the said bolt, dogs preventing the forward movement of the said post, a trip-lever actuated by the said bolt, and a registering device driven by the said trip-lever, as and for the purposes described. 115

In testimony whereof I have affixed my signature in presence of two witnesses.

WILLIAM FESSENDEN BEASLEY.
